UNITED STATES PATENT OFFICE.

SAMUEL I. BERGER, OF NEWARK, NEW JERSEY.

DESIGN FOR AN AUTOMOBILE TOY.

Application filed January 17, 1927. Serial No. 20,410. Term of patent 7 years.

To all whom it may concern:

Be it known that I, SAMUEL I. BERGER, a citizen of the United States, and residing at Newark, in the county of Essex and State of New Jersey, have invented a new, original, and ornamental Design for Automobile Toy, of which the following is a specification, reference being had to the accompanying drawings, forming part hereof. The figure is a perspective view of the automobile toy.

I claim:

The ornamental design for an automobile toy as shown.

SAMUEL I. BERGER.
